UNITED STATES PATENT OFFICE.

JOHN DEY AND ALEXANDER DEY, OF SYRACUSE, NEW YORK, ASSIGNORS TO DEY TIME REGISTER COMPANY, OF SYRACUSE, NEW YORK, A CORPORATION OF NEW YORK.

WORKMAN'S TIME-RECORDER.

No. 908,974.

Specification of Letters Patent.

Patented Jan. 5, 1909.

Application filed May 25, 1905. Serial No. 262,211.

To all whom it may concern:

Be it known that we, JOHN DEY and ALEXANDER DEY, residing at Syracuse, in the county of Onondaga and State of New York, have invented certain new and useful Improvements in Workmen's Time-Recorders, of which the following is a full, clear, and exact description, such as will enable others skilled in the art to which it applies to make and use the same.

This invention relates broadly to time recorders although certain features thereof are of value in other relations.

One of the objects thereof is to provide efficient means whereby clockwork is adapted intermittently to actuate a member without abnormally burdening the same at the time of actuation.

Another object is to provide means of simple and efficient construction and ready manipulation for the manual actuation of a time recorder.

Another object is to provide practical and accurately acting means, both manually and automatically actuated for placing a record card in the desired position relative to printing mechanism.

Another object is to provide means in connection with a time recorder casing adapted to render the same substantially dust proof and yet permit ready access to the parts inclosed.

Another object is to provide means in connection with time recorders for preventing false registration.

Other objects will be in part obvious and in part pointed out hereinafter.

The invention accordingly consists in the features of construction, combinations of elements and arrangement of parts which will be exemplified in the apparatus and devices hereinafter described and the scope of the application of which will be indicated in the following claims.

In the accompanying drawings, wherein is shown one of various possible embodiments of the several features of our invention, Figure 1 is a sectional elevation of the same. Fig. 2 is a similar view of certain parts appearing in Fig. 1 shown on a larger scale and isolated from the surrounding mechanism. Fig. 3 is a similar view showing certain parts appearing in Fig. 2 in a slightly different position. Fig. 4 is a plan of certain parts shown in Fig. 2. Fig. 5 is a sec-

tional plan. Fig. 6 is a perspective view of a card receiver and parts associated therewith. Fig. 7 is a similar view of certain parts co-acting with the card receiver in positioning the card. Figs. 8 to 10 are similar views of certain parts shown in Fig. 7, the same being shown at different stages of the operation of this device. Fig. 11 is a plan of certain parts shown in Fig. 6. Fig. 12 is an elevation of the free end of an actuating lever together with the parts co-acting therewith. Fig. 13 is a similar view showing the same parts in another position.

Similar reference characters refer to the same parts throughout the several views.

As conducing to a better understanding of certain features of our invention, it may here be noted that in clock-driven mechanism now in general use in which parts are intermittently actuated, an abnormal burden is laid on the clockwork at the time of said actuation, thus rendering it necessary for the latter to be sufficiently heavy and powerful to drive these parts, even though such actuation occupy but a minute fraction of the total time during which the clockwork is in operation. This necessitates heavier parts, with a consequent expenditure of material and waste of space, than would be necessary if the work required of the clock were more uniformly distributed. It may also here be noted that in time recorders it is of considerable importance that the manually-actuated parts be readily and quickly manipulated without interfering with the convenient opening of the casing in such manner as to give access to all parts of the recorder. It may also be noted at this point that if it be attempted to position a record card relative to the printing mechanism in such a loosely held condition as readily to be inserted and removed from the card receiver, the alignment of the impressions received thereon is poor. Another feature of interest at this point is that with the use of a flexibly driven printing wheel it is sometimes possible for the workman or other user of the instrument to so cause the printing wheel to swing as to result in a false registration of the time. The above and other defects are eliminated and many advantages attained in constructions of the nature of that hereinafter described.

Referring now to the illustrative embodiment shown in the drawings, there appears in

Fig. 1 a casing 1 through which projects a hand lever 2 pivoted at 3 to the frame of the instrument. This lever is provided with a hand rest 4 pivoted thereto and passes 5 through a plate 5 best shown in Fig. 13 of the drawings. Beneath this plate, which is slotted as shown at 6 to permit a free movement of the lever 2, is what may be termed a "shutter" 7 secured to the plate by means of 10 pins 8 and 9 passing through the inclined slots 10 and 11 in said shutter. Shutter 7 is provided with a projecting portion 12 extending across the slot 6 and having an inclined lower edge 13, and beneath this portion is a 15 recess 14 bounded upon its lower side by the inclined edge 15. Lever 2 is normally depressed upwardly, by means hereinafter described, and occupies the position shown in Fig. 12 of the drawings by reason of its 20 engagement with the inclined edge of the projecting portion 12, thus raising the shutter and throwing the same laterally, owing to the inclined conformation of slots 10 and 11. The opening within the plate 5 is thus closed 25 about the lever 2 with the latter in its normal position, preventing the entry of dust, dirt or other foreign matter. A free downward movement, however, is permitted the lever as upon pressing the same in such direction 30 it engages the inclined edge 15 and throws the shutter downwardly and laterally, as shown in Fig. 13 of the drawings. Upon the lever being released, however, it again assumes the position shown on Fig. 12 with the 35 shutter 7 closing the slot 6.

Lever 2, which is preferably of bell crank form, is connected as by the slot 16 and screw 17 with an arm 18 fast upon a rock shaft 19 journaled upon the frame of the instrument. As the lever is depressed the rock shaft 19 is thus oscillated in its bearings, a comparatively slight angular movement of the lever corresponding with a considerable rocking of the shaft owing to the eccentric 40 disposition of the pivot of the former with reference to the axis of the shaft. Rock-shaft 19 has fixed thereon an arm 20 connected as by a rod 21 having thereon nuts 22 and spring 23 with a pressure lever 24 pivotally mounted upon the post 25 and adapted to co-act with parts hereinafter described in forcing a recording surface in contact with type bearing members and thus producing a record on said surface.

Likewise fixed upon rock-shaft 19 is an arm 26 normally drawn in a rearward and downward direction by means of a heavy spring 27, as shown in Fig. 1 of the drawings. This arm has pivotally mounted thereon a 55 rod 28 for a purpose hereinafter described.

Recurring now to Fig. 1 of the drawings, there is shown a vertical shaft 29 driven by clockwork of any desired type and having on its lower end a bevel pinion 30 meshing with 60 a similar pinion 31 upon the shaft 32. Like-

wise fixed upon this shaft is a spur pinion 33 driving by means of the idle gear 34 and pinions 35 a gear 36, hereinafter referred to. It may here be noted that by the term "time driven member" as used throughout the following claims is meant any member driven from clockwork or means equivalent thereto. Gear 34 preferably intermeshes with and drives certain other mechanism broadly denoted by the character 34^a. This mechanism by which an additional type-wheel or wheels are driven will not be described in detail as it forms no part of the present invention.

Upon shaft 32 is fixed what may be termed 80 a minute wheel 37, the same being provided about its circumference with a number of type 38, comprising numerals ranging, in this illustrative embodiment, from 0 to 59. These type are adapted to co-act with the 85 printing ribbon 39 mounted upon suitable spools 40 and 41 and fed by mechanism not herein shown as it forms in itself no part of the present invention. Minute wheel 37 which is mounted upon a frame 42 is provided with a lug 43 adapted to co-act with a star wheel 44 mounted upon a shaft 45 which has fixed thereon what may be termed an hour wheel 46 having about its circumference type bearing numerals which range, in this 90 illustrative embodiment of our invention, from 1 to 24. A second star wheel 47 fixed upon the shaft 45 is provided with what may be termed a "brake" or lock 48 pivoted at 49 and normally held against the same as 100 by means of a spring 50, the other end of which is secured to the frame 42 of the instrument. The free end of brake 48 terminates in an extended arm 51 having a rectangularly bent tip 52 resting in engagement with a cam 53 formed upon minute wheel 37. Cam 53 is provided with a single depression 54 so positioned as to be brought opposite the tip 52 at the instant of engagement of star wheel 44 by the lug 43. In this 105 manner the brake 48 may be thrown outwardly against the force of spring 50 by the star wheel 47 as the star wheel 44 is moved by pawl 43. After this operation has taken place, the cam 53 moves so as to bring the tip 110 52 upon the outer raised surface thereof, thus locking the brake 48 in engagement with star wheel 47 and preventing further movement of the shaft 45.

Mounted upon a pin 55 upon minute 120 wheel 37 is a roller 56 adapted to co-act with what may be termed a "storage lever" 57, best shown in Figs. 2, 3 and 4 of the drawings. This lever is mounted upon the frame 42 by means of a pin 58 and is provided with 125 an extended arm 59 connected by a spring 60 with the frame. The latter member thus tends to rock the lever 57 about the pivot pin 58 and hold the same in its lowermost position, determined by a stop 61. The free 130

end of lever 57 is offset, as shown in Fig. 4 of the drawings, so as to rest within the path of roller 56 and the lower surface thereof is shaped substantially as shown in Fig. 2 of the drawings. This surface comprises, broadly, four portions, namely, a portion 62 normally inclined toward the path of travel of roller 56, a portion 63 inclined away from said path, a third portion 64 substantially parallel to said path, and a fourth portion 65 of inclination similar to the portion 63. The operation of this feature of our invention is substantially as follows: Assuming that the lug 43 is approaching the star wheel 44, the roller 56 is so positioned as to engage the inclined portion 62 throughout a considerable angular distance and gradually raise the lever 57 extending the spring 60. At the moment at which the hour wheel 46 is actuated, the roller 56 is engaged by the inclined portion 63 of the lever and owing to the sharp inclination of this portion the spring 60 tends to propel the minute wheel in a forward direction, thus aiding the clock-work in moving the intermittently actuated parts. The hour wheel is thus moved so as to be in position to print the next succeeding hour and any accidental or intentional oscillation of the same so as incorrectly to print the same is prevented by the lever 57 which locks the minute wheel against movement in a reverse direction. At one minute past the hour, moreover, the lever is drawn further in a downward direction by the spring 60 and the portion 65 thereof engages the roller 56 preventing any retraction of the minute wheel from this position. The hour wheel is thus maintained in the position to which it has been moved until it is securely locked therein by the brake 48, the action of which has been above described.

Positioned within the casing of the instrument is a card receiver 66, the depth within which a card or other record receiving member may be inserted being determined by a movable abutment 67, best shown in Fig. 7 of the drawings. Referring now to this figure, the abutment or stop 67 is shown formed upon or secured to a strap 68 adjustably clamped about a sleeve 69 as by means of screws 70. This sleeve is slidably mounted upon a guide rod 71 which in turn is mounted in fixed relation to the casing of the instrument. Secured upon sleeve 69 as by means of collars 72 is a ratchet or rack 73 actuated by the following means. Upon a sleeve 74, driven through gear 36, as above set forth, is a plate 75 having pivotally mounted thereon at a point eccentric to its axis, as by means of screw 76, a swinging cam member 77. The movement of this member is limited by means of stop pins 78 and 79 in such manner as with a certain direction of rotation to cause the same to depend from plate 80, as shown in Fig. 7 of the drawings, the cam in

this position resting against stop 78. Upon frame member 81 is positioned a strap 82 having its ends bent so as to form bearings for a rock shaft 83 detachably held in position as by means of the lynch pins 84 and 85. Rock-shaft 83 is provided at one end with an arm 86 engaged by a spring 87 coiled about the shaft and secured to the strap 82 in such manner as to tend to throw the arm in an upward direction. The free end of arm 86 projects within the path of travel of the depending cam 77, assuming the same to be rotating in the direction indicated by the arrow in Fig. 7 of the drawings. The arm 86 is thus periodically depressed, causing a periodical rocking of the shaft 83. Upon the cam being rotated in the opposite direction, however, it passes over arm 86 without moving the same, as indicated in Fig. 8 of the drawings. The remaining end of shaft 83 terminates in a yoke 88 within which is journaled a bent rod 89, the free end of which forms a pawl 90 adapted to engage the rack 73 and actuate the same, a suitable spring 91 being provided beneath the yoke 88 tending to throw the pawl into engagement therewith. A holding pawl 92 is journaled within a yoke 93 fixed upon the strap 82, a suitable spring 94 tending to maintain this pawl in engagement with the rack. It will thus be seen that as shaft 83 is rocked back and forth, the pawl 90 raises the rack step by step and pawl 92 holds the same in its raised position. Assuming the sleeve 74 to rotate once in twenty-four hours, the abutment 67 is thus successively raised for a predetermined distance at the end of each such interval of time.

Likewise mounted upon frame member 81 is a standard 95 having mounted thereon a releasing member 96 normally pressed by a spring 97 in a direction away from pawls 90 and 92. This member is secured to the standard by screws 98 and 99, the former of which passes through a straight slot 100 and the latter of which is positioned within a rectangular slot 101, as shown in Fig. 7 of the drawings. Member 96 is provided with inclined surfaces 102 and 103, the former of which is adapted to be engaged by a pin 104 upon the sleeve 69, and the latter of which is adapted to engage the holding pawl 92. The upper end of the releasing member is inclined downwardly, as shown at 105 in the drawings, and forms at the side adjacent pawl 90 a tooth 106 having positioned beneath the same a projection 107.

Preferably mounted upon the casing of the instrument is a strap 108 within the depending ends 109 of which is journaled a shaft or spindle 110 having thereon a pinion 111 intermeshing with a rack 112 secured to sleeve 69. Upon a shaft 110 is fixed a cylinder 113 about which are printed certain characters, preferably the several days of the week, and formed in the casing of the instrument immediately

opposite the cylinder front portion 113, as shown in Fig. 1 of the drawings, is a window 115 of such dimensions as to expose a portion of the outer surface of cylinder. In this 5 manner, as the sleeve is moved by the mechanism above described, the cylinder 113 is turned so as to indicate the position of the abutment by the matter displayed through the window 115.

10 The operation of the above features of our invention is substantially as follows: Assuming the sleeve 74 to be rotated once in twenty-four hours in the direction indicated by the arrow in Fig. 7 of the drawings, the 15 cam 77 periodically forces the arm 86 downwardly and releases the same, the spring 87 throwing this arm upwardly after each depression, thus oscillating the rock shaft 83. This movement causes the intermittent 20 cent of the rack 73 and parts associated therewith, as above described. Upon the rack reaching the uppermost limit of its desired path of travel, however, the pin 104 engages the inclined surface 102 throwing the member 96 into the path of travel of the actuating pawl 90. Upon the next downward oscillation of this pawl the same passes beneath the tooth 106 and is held from engagement with the rack by the member 96.

25 As the pawl swings upwardly when in this position, it draws the releasing member in a corresponding direction and the inclined surface 103 engaging the holding pawl 92 forces the same away from the rack, thus 30 permitting sleeve 69 with the parts associated therewith to fall to the lowermost limit of its path of travel. At the next subsequent downward movement of the actuating pawl 90 the same engages the projection 107 35 and forces member 96 downwardly until the screw 99 passes out of the vertical portion of slot 101 into which it has been moved by the pawl. Spring 97 then swings the releasing member out of the path of travel of the 40 pawls and the ratchet is again raised as previously described. The above series of operations is repeated as often as is desired, although in this illustrative embodiment it is intended that the same occur once each 45 week, thus resulting in an intermittent upward movement of the abutment 67 each night and the fall of the same throughout the whole of its path of travel at the end of the week.

50 Card receiver 66 comprises an outer casing 116 within which are mounted the card engaging members or "grippers" 117 and 118 having respectively formed thereon or secured thereto the cover plates 119 and 120.

55 Member 118 has secured thereto a suitably supported strip 121 connected as by the strap 122 with a rack 123 slidably mounted in the guide 124. In this manner the card gripper 117 is moved laterally with respect 60 to the printing mechanism as the rack 123

makes a corresponding movement. Rack 123 intermeshes with a pinion 125 fixed upon a spindle 126, the upper end of which forms a disk 127 provided with a central recess 128 and a similar recess 129 eccentrically positioned with respect to its axis. Mounted upon the casing of the instrument above the disk 127 is a door 130 adapted when open to give ready access to the interior of the instrument. Journalized upon this door as 75 within a bearing 131 is a spindle 132 having thereon a disk or face plate 133 on which is formed a rounded projection 134 adapted to fit within the recess 128. Eccentrically positioned in disk 133 is a round-pointed screw 80 135 adapted when the door is in closed position to enter the recess 129 above described. It will thus be seen that with the door 130 in closed position, the disks 127 and 133 form a secure and yet readily detachable connection between the spindles 126 and 132. Fixed upon the latter spindle is a crank 136 provided with a handle or knob 137 for purposes of ready manipulation. This crank, which is preferably of resilient material, is provided with a locking lug or projection 138 adapted normally to press against a locking plate 139 and to tend to enter recesses 140 positioned about the circumference thereof. This plate is provided with a series of openings 141, preferably six in number and corresponding in size to an opening 142 formed within the crank 136. The relative positions of card 90 engaging members 117 and 118 is determined by means hereinafter described.

The method of use of the above features of our invention is substantially as follows: Assuming that it is desired that the card grippers 117 and 118 occupy a certain position with reference to the printing wheels 37 and 4C, the crank 136 is rotated so as to shift these members, which are connected as hereinafter set forth into the desired position by means of pinion 125 and rack 123, 110 this position being readily found by rotating the crank until the opening 142 therein registers with an opening 141 disclosing matter indicative of the position which it is desired that the card engaging members assume. In order to rotate the crank 136 it is necessary merely that the same be depressed so as to prevent the entry of the locking lug 138 within the recesses 140 until the crank has reached the desired position, whereupon 115 it is released and automatically locked in such position as above described.

If it be desired that the card engaging members or grippers occupy the same lateral position relative to the printing mechanism 125 throughout a considerable period of time, and it be desired that they be locked in such position in such manner as to obviate the chance of the same being moved without permission, this result may be attained by 130

the following means: Referring now to Fig. 6 of the drawings, there is shown a locking slide 143 secured to the inner surface of door 130 as by screws 144 and slots 145. This slide is bent at one end so as to form the finger-piece 146 and is flanged as shown at 147 so as to enter radial slots 148 cut about the surface of disk 133.

By means of the above-described lock, if 10 it is desired that lateral manipulation of the card engaging members be done away with the door 130 is unlocked and opened and the locking slide 143 thrust within the slot 148 corresponding to the desired lateral position 15 of record card. Door 130 is then closed and locked by any desired means and lateral manipulation of the members 117 and 118 prevented.

Recurring now to the gripper 117, the 20 same is provided with a strip 149 secured thereto as by means of screw 150 and having at its free end a flange 151, slotted as shown at 152 and passing over the end of the strip 121 above described. The latter member is 25 slotted so as to form a sliding joint with the flange 151, as shown in Fig. 6 of the drawings. A spiral spring 153 is secured to strips 121 and 149 and tends normally to draw the card engaging members 117 and 118 toward 30 one another. Within strips 121 and 149 are slots 154 and 155 through which passes the rod 28 bent, as shown at 156 in Figs. 5 and 6 of the drawings. This rod normally engages one end of the slot 155 at its bent portion 156 35 and the free end of the rod passes through the slot 154 in strip 121. Slots 154 and 155 are thus held out of alinement by the rod 28, the spring 153 thus being stretched and the members 117 and 118 being held apart so as 40 to permit the ready entry of a record card therebetween. If it be desired now that the record card, being within the receiver, be held against the member 118 so as to be accurately positioned with respect to the 45 printing mechanism, the rod 28 is thrust forwardly by hand lever 2 and arm 26, thus forcing the straight portion thereof within the slots 154 and 155 bringing these openings more nearly into alinement. Spring 153 is 50 thus permitted to draw the member 117 toward the member 118 and grip the card during the printing operation.

It will be apparent that the card grippers 117, 118 may be simultaneously moved by 55 means of the crank and rack heretofore referred to, said grippers being so connected by means of the spring 153 and the slotted connection 152 that the gripper 117 moves with the gripper 118 whenever the latter is manually shifted. It is only when the movement 60 of the rod 28 throws its inclined portions in such position to permit spring 153 to draw the gripper 117 toward the gripper 118 that the said grippers have movement relative to 65 each other, it being understood that in the

operation of the machine the gripper 118 is first positioned relative to the printing mechanism to assure the position of the card, the gripper 117 moving with the first named gripper, and that the latter then moves relative to said first named gripper in order to move the card against the latter. 70

It will thus be seen that we have provided efficient and inexpensive apparatus and devices for accomplishing the several objects of 75 our invention and that this apparatus is of durable and non-complicated construction and simple action. The construction, moreover, although compact and simple, is nevertheless adjustable and the parts are so formed 80 and arranged as to render readily accessible all portions of the instrument.

The above illustrative embodiment of our invention embodies many advantageous features, some of which have been herein 85 specifically pointed out or will be apparent from the matter herein set forth, and others of which can be appreciated only by those understanding the severe conditions of practical use which this instrument is well adapted 90 to withstand.

As many changes could be made in the above construction and many apparently widely different embodiments of our invention could be made without departing from 95 the scope thereof, we intend that all matter contained in the above description or shown in the accompanying drawings shall be interpreted as illustrative and not in a limiting sense. We desire it also to be understood that 100 the language used in the following claims is intended to cover all of the generic and specific features of the invention herein-described and all statements of the scope of the invention, which as a matter of language, 105 might be said to fall therebetween.

Having described our invention, what we claim as new and desire to secure by Letters Patent, is:—

1. In a time recorder, in combination, a 110 casing, a member adapted to swing relative to said casing, a member journaled in fixed relation to said casing, a substantially co-axial member journaled in fixed relation to said first member, a projection upon said 115 co-axial member adapted to engage said second member and transmit motion to the same, and manually - controlled means mounted upon said first member adapted to impart motion to said third member. 120

2. In a time recorder, in combination, a 125 casing, a door hinged thereto, a member journaled in fixed relation to said casing, a member journaled in fixed relation to said door, an eccentrically positioned projection upon one of said members adapted to engage and transmit motion to the other thereof, and manually-controlled means mounted upon said door adapted to impart motion to said first-mentioned member. 130

3. In a time recorder, in combination, a casing, a rotatable member, manually-controlled means positioned without said casing adapted to impart movement to said rotatable member, and manually-controlled means within said casing operable independently of said first-named manually-controlled means and adapted positively to lock said rotatable member against movement.
4. In a time recorder, in combination, a casing, a rotatable member, manually-controlled means positioned without said casing adapted to impart movement to said rotatable member, and manually-controlled means within said casing operable independently of said first-named manually-controlled means and adapted to lock said rotatable member against movement in either direction.
5. In a time recorder, in combination, a casing, a rotatable member having an irregular surface, a manually movable member within said casing adapted to be thrown into engagement with said irregularities and positively lock said rotatable member in a predetermined position against movement in either direction, and manually-controlled means without said casing operable independently of said manually movable member and adapted to impart movement to said rotatable member.
6. In a time recorder, in combination, a casing, a rotatable member having an irregular surface, a movable member within said casing adapted to be thrown into engagement with said irregularities and positively lock said rotatable member in a predetermined position against movement in either direction, manually-controlled means without said casing adapted to impart movement to said rotatable member, and a visual indicator adapted to indicate the position of said rotatable member.
7. In a time recorder, in combination, a casing, a rotatable member having a series of substantially radial slots within the same, a movable member within said casing adapted to be moved into engagement with said slots and positively lock said rotatable member in a predetermined position, and manually-controlled means without said casing adapted to impart movement to said rotatable member.
8. In a time recorder, in combination, a casing, a rotatable member extending through said casing, manually-actuated means adapted to impart motion to said rotatable member, manually-controlled means positioned without said casing adapted to lock said rotatable member against movement in either direction, and manually-controlled means positioned within said casing adapted to lock said member against movement in either direction.
9. In a time recorder, in combination, a casing, a rotatable member, manually-actuated means adapted to impart motion to said rotatable member, independent locking means positioned within and without said casing and adapted to lock said rotatable member in a predetermined position, laterally movable card-receiving means, and means connecting said card-receiving means and said rotatable member and adapted to control the same in accordance with the position of said rotatable member.
10. In a time recorder, in combination, a casing, a door positioned upon said casing, a rotatable member journaled within said door and projecting from the same, manually-controlled means mounted without said door adapted to impart motion to said rotatable member, independent manually-controlled locking means positioned within and without said casing adapted to lock said rotatable member against movement in either direction, and a visual indicator adapted to indicate the position of said rotatable member.
11. In a time recorder, in combination, a rotatable member having an irregular surface, a movable member adapted to be thrown into engagement with said irregularities and positively lock said rotatable member in a predetermined position against movement in either direction, a visual indicator adapted to indicate the position of said rotatable member, laterally movable card receiving means, and means connecting said rotatable member and said card receiving means and controlling the same in accordance with the position of said rotatable member.
12. In a time recorder, in combination, a casing, a manually actuated rotatable member having an irregular surface, a movable member adapted to be thrown into engagement with said irregularities and lock said rotatable member in a predetermined position, said locking means being positioned within said casing, manually-actuated means without said casing adapted to impart motion to said rotatable member, laterally movable card-receiving means, and means connecting said card-receiving means and said rotatable member and controlling the same in accordance with the position of said rotatable member.
13. In a time recorder, in combination, a casing, a rotatable member, manually-controlled means adapted to impart motion to said rotatable member, independent locking means positioned within and without said casing and adapted to lock said rotatable member in a predetermined position, laterally movable card-receiving means, and means connecting said card-receiving means and said rotatable member and adapted to control the same in accordance with the position of said rotatable member.
14. In a time recorder, in combination, a card engaging member, means adapted positively to hold the same against movement in either direction, a second card-engaging

- member, a spring tending to draw together said card-engaging members, and manually controlled means adapted to oppose said spring and hold said card engaging members 5 against movement toward each other.

15. In a time recorder, in combination, a card-engaging member, manually-actuated means adapted positively to move the same in either direction, a second card-engaging member, a spring tending to draw together said card-engaging members, and manually-controlled means adapted to oppose said spring and hold apart said card-engaging members.

16. In a time recorder, in combination, a 15 card-engaging member, means adapted positively to move the same in either direction, a second card-engaging member, a spring tending to draw said card-engaging members toward one another, and manually-controlled means adapted to oppose said spring and hold apart said card-engaging members.

17. In a time recorder, in combination, two relatively movable card-engaging members, a spring tending to move the same toward one another, a pair of members respectively disposed in substantially fixed relation to said relatively movable members, and a member engaging both of said second-mentioned members and adapted to oppose said 25 spring and hold apart said relatively movable members.

18. In a time recorder, in combination, two relatively movable card-engaging members, a spring tending to move the same toward one another, a pair of members respectively disposed in substantially fixed relation to said relatively movable members, a member engaging both of said second-mentioned members and adapted to oppose said 35 spring and hold apart said relatively movable members, and manually-actuated means adapted to move said engaging member and permit said spring to draw toward one another said relatively movable card-engaging members.

40 19. In a time recorder, in combination, two relatively movable card-engaging members, a spring tending to move the same toward one another, a pair of members respectively disposed in substantially fixed relation to said relatively movable members, and a manually-controlled member engaging said 45 two last-mentioned members, said manually-controlled member being adapted to assume two positions, in one of which said spring is opposed and said card-engaging members held apart, and in the other of which said 50 spring is released and said card-engaging members drawn toward one another.

55 20. In a time recorder, in combination, two relatively movable card-engaging members, a spring tending to move the same toward one another, a pair of members respectively disposed in substantially fixed relation to said relatively movable members, and a 60 manually-controlled rod comprising two 65 relatively inclined portions adapted to engage said last-mentioned members, said rod being adapted upon one of said portions engaging said members to oppose said spring and hold apart said card-engaging members, and upon the other thereof engaging said members to release said spring and permit the same to draw together said card-engaging members.

70 21. In a time recorder, in combination, 75 two relatively movable card-engaging members, a spring tending to move the same toward one another, a pair of members respectively disposed in substantially fixed relation to said relatively movable members, and a 80 manually-controlled rod passing through openings in said last-mentioned members, said rod being adapted to assume two positions, in one of which said spring is opposed and said members held apart, and in the 85 other of which said spring is released and said card-engaging members drawn together thereby.

22. In a time recorder, in combination, 90 two relatively movable members, a spring tending to move the same toward one another, a pair of members respectively disposed in substantially fixed relation to said relatively movable members, a rod passing through openings in said two last-mentioned 95 members, said rod comprising two relatively inclined portions and being adapted upon one of said portions engaging said members to oppose said spring and hold apart said card-engaging members, and upon the other of said portions engaging said members to release said spring and permit the same to draw together said card-engaging members.

100 23. In a time recorder, in combination, 105 two relatively movable card-engaging members, manually-actuated means adapted positively to move one of said members, a pair of members respectively disposed in substantially fixed relation to said relatively movable members, a member engaging said 110 last-mentioned members and adapted to oppose said spring and hold said card-engaging members apart, and manually-actuated means adapted to move said member and permit said spring to draw together said 115 card-engaging members.

24. In a time recorder, in combination, 120 two relatively movable card-engaging members, manually-actuated means adapted positively to move one of said card-engaging 125 members, a spring tending to draw together said card-engaging members, a pair of members respectively disposed in substantially fixed relation to said relatively movable card-engaging members, a rod passing through openings in said last-mentioned members, said rod comprising two relatively inclined portions and being adapted upon one of said portions engaging said members to oppose said spring and hold apart said 130

card-engaging members, and upon the other of said portions engaging said members to release said spring and permit the same to draw together said card-engaging members, 5 and manually-actuated means controlling the position of said member.

25. In a time recorder, in combination, a movable member, a member adapted to hold the same in the position into which it is 10 moved, a spring tending to maintain said holding member in operative position, a more powerful spring, and means controlled by said second spring adapted to overcome said first spring and move said holding member into inoperative position.

26. In a time recorder, in combination, printing mechanism, a movable abutment adapted to limit the movement in one direction of a co-acting record card, a toothed 20 member operatively connected with said abutment and adapted to impart movement thereto, an actuating pawl adapted to move said toothed member, a holding pawl co-acting with said toothed member, and means 25 controlled by said toothed member and movable relatively thereto and operated by said actuating pawl adapted to throw said holding pawl into inoperative position.

27. In a time recorder, in combination, 30 printing mechanism, an abutment adapted to limit the movement in one direction of a co-acting record card, a toothed member operatively connected with said abutment, a holding pawl co-acting with said toothed member, a spring tending to maintain said holding pawl in operative position with relation to said toothed member, a more powerful spring, and means actuated by said second spring adapted to overcome said first 40 spring and move said holding pawl into inoperative position.

28. In a time recorder, in combination, printing mechanism, a movable abutment adapted to limit the movement in one direction of a co-acting record card, a toothed member operatively connected with said abutment, actuating and holding pawls co-acting with said toothed member, clock-actuated means adapted intermittently to operate said actuating pawl, a spring tending 50 to hold said holding pawl in operative relation to said toothed member, and means controlled by said toothed member and operated by said actuating member adapted to overcome said spring and move said holding member into inoperative position.

29. In a time recorder, in combination, a toothed member, holding and actuating pawls co-acting with said toothed member, 60 clock-controlled means adapted intermittently to operate said actuating pawl, and automatic means actuated by said actuating pawl adapted simultaneously to maintain

said holding and said actuating pawls out of engagement with said toothed member.

65

30. In a time recorder, in combination, printing mechanism, an abutment adapted to limit the movement in one direction of a co-acting record card, a toothed member operatively connected with said abutment, holding and actuating pawls co-acting with said toothed member, clock-controlled means adapted intermittently to operate said actuating pawl, and a single member adapted upon said actuating pawl being operated a predetermined number of times to hold said actuating and holding pawls simultaneously out of engagement with said toothed member, said last-mentioned single member being controlled in accordance with the position of said toothed member and operated by said actuating pawl.

31. In a time recorder, in combination, printing mechanism, an abutment adapted to limit the movement in one direction of a co-acting record card, a toothed member operatively connected with said abutment, holding and actuating pawls co-acting with said toothed member, clock-controlled means adapted to operate said actuating pawl, and a spring-pressed member adapted to be thrown into the path of travel of said actuating pawl by said toothed member.

85

32. In a time recorder, in combination, printing mechanism, an abutment adapted to limit the movement in one direction of a co-acting record card, a toothed member operatively connected with said abutment, holding and actuating pawls co-acting with said toothed member, clock-controlled means adapted to operate said actuating pawl, a spring-pressed member having an inclined portion adapted to be engaged by a co-acting part upon said toothed member, said spring-pressed member being adapted to be thrown into the path of travel of said actuating pawl upon said engagement, a tooth upon said spring-pressed member adapted to be engaged and raised by said actuating pawl and means adapted to throw said spring-pressed member against said holding pawl and release the same upon said member being raised through said tooth.

105

33. In a time recorder, in combination, printing mechanism, a movable abutment adapted to limit the movement in one direction of a co-acting record card, a toothed member operatively connected with said abutment, holding and actuating pawls co-acting with said toothed member, clock-controlled means adapted to operate said actuating pawl, a spring-pressed member, means upon said toothed member adapted to throw said spring-pressed member into the path of travel of said actuating pawl, and means upon said spring-pressed member adapted to 110

115

120

125

be engaged and moved by said actuating pawl, said spring-pressed member being adapted upon being engaged and moved by said actuating pawl to throw said holding 5 pawl into operative position.

34. In a time recorder, in combination, printing mechanism, a movable abutment adapted to limit the movement in one direction of a co-acting record card, a toothed 10 member operatively connected with said abutment, holding and actuating pawls co-acting with said toothed member, clock-controlled means adapted to operate said actuating pawl, a spring-pressed member, means 15 upon said toothed member adapted to throw said spring-pressed member into the path of travel of said actuating pawl, and means upon said spring-pressed member adapted to be engaged and moved by said actuating 20 pawl, said spring-pressed member being adapted upon being engaged and moved by said actuating pawl to throw said holding pawl into inoperative position and maintain said actuating pawl out of engagement with 25 said toothed member.

35. In a time recorder, in combination, printing mechanism, a movable abutment adapted to limit the movement in one direction of a co-acting record card, a toothed 30 member operatively connected with said abutment, holding and actuating pawls co-acting with said toothed member, a member adapted to be engaged by parts controlled in accordance with the position of said toothed 35 member and thrown into the path of travel of said actuating pawl, a tooth upon said last-mentioned member adapted to be engaged by said actuating pawl and said member raised thereby, and an inclined surface 40 upon said member adapted to engage and throw out said holding pawl upon the said raising taking place.

36. In a time recorder, in combination, printing mechanism, an abutment adapted 45 to limit the movement in one direction of a co-acting record card, a toothed member operatively connected with said abutment, actuating and holding pawls co-acting with said abutment, clock-controlled means 50 adapted upon rotation in one direction to operate said actuating pawl, means adapted to prevent the operation of said actuating pawl upon the direction of rotation of said clock-controlled means being reversed, a spring- 55 pressed member adapted to be engaged by parts controlled by said toothed member and thrown into the path of travel of said actuating pawl, said spring-pressed member being provided with parts adapted to be engaged 60 by said actuating pawl and the member moved thereby and an inclined portion adapted upon said moving taking place to throw said holding pawl into inoperative position.

37. In a time recorder, in combination, printing mechanism, an abutment adapted 65 to limit the movement in one direction of a co-acting record card, a toothed member operatively connected with said abutment, actuating and holding pawls co-acting with 70 said abutment, clock-controlled means adapted upon rotation in one direction to operate said actuating pawl, means adapted to prevent the operation of said actuating pawl upon the direction of rotation of said clock- 75 controlled means being reversed and a spring-pressed member adapted to be engaged by parts controlled by said toothed member and thrown into the path of travel of said actuating pawl, said spring-pressed member being 80 provided with parts adapted to be engaged by said actuating pawl and the member moved thereby, an inclined portion adapted upon said moving taking place to engage said holding pawl and throw the same into inoperative 85 position, and parts adapted upon the member being moved by said actuating pawl to maintain both of said pawls out of engagement with said toothed member.

38. In a time recorder, in combination, printing mechanism, an abutment adapted 90 to limit the movement in one direction of a co-acting record card, a toothed member operatively connected with said abutment, actuating and holding pawls co-acting with 95 said toothed member, clock-controlled means adapted intermittently to operate said actuating pawl, a spring-pressed member, means controlled by said toothed member adapted to throw said spring-pressed member into the 100 path of travel of said actuating pawl, means upon said spring-pressed member adapted to be engaged and raised by said actuating pawl, said spring-pressed member being adapted upon being so raised to throw said 105 holding pawl out of engagement with said toothed member, and means adapted to maintain said spring-pressed member in the position into which it is thrown.

39. In a time recorder, in combination, an 110 abutment adapted to limit the movement in one direction of a co-acting record card, a toothed member operatively connected with said abutment, actuating and holding pawls co-acting with said toothed member, a sup- 115 porting member, a spring-pressed member having a slotted connection therewith, and means controlled by said toothed member adapted to throw said spring-pressed member into the path of travel of said actuating 120 pawl, said spring-pressed member being provided with a pair of projecting portions adapted to be engaged by said actuating pawl and said spring-pressed member being adapted on one of said portions being en- 125 gaged by said actuating pawl to be raised thereby and to throw said holding pawl out of operative relation with said toothed mem-

ber and upon the other of said projecting portions being engaged by said actuating pawl to be depressed thereby and release said holding pawl.

5 40. In a time recorder, in combination, printing mechanism, an abutment adapted to limit the movement in one direction of a co-acting record card, a toothed member operatively connected with said abutment, actuating and holding pawls co-acting with said toothed member, clock-controlled means adapted to operate said actuating pawl, a supporting member, a spring-pressed member having a slotted connection with said 10 supporting member at two points, one of the slots comprising portions inclined with reference one to another, means controlled by said toothed member adapted to engage said spring-pressed member and throw the same 15 within the path of travel of said actuating pawl, a projection upon said spring-pressed member adapted to be engaged by said actuating pawl and the same raised thereby, said spring-pressed member being provided with 20 a portion adapted upon the same being raised to engage and throw into inoperative position said holding pawl, and a projection upon said spring-pressed member adapted to be engaged by said actuating pawl and the 25 member depressed therethrough.

30 41. In a time recorder, in combination, printing mechanism, an abutment adapted to limit the movement in one direction of a co-acting record card, a toothed member operatively connected with said abutment, actuating and holding pawls co-acting with said toothed member, clock-controlled means adapted to operate said actuating pawl, a spring-pressed member, means controlled by 35 said toothed member adapted to throw said spring-pressed member into the path of travel of said actuating pawl, said spring-pressed member being provided with a projection adapted to be engaged by said actuating pawl and the member raised therethrough, and means adapted to prevent a retraction of said spring-pressed member upon the same being raised, said spring-pressed member being provided with a portion 40 adapted to engage and render inoperative said holding pawl upon being raised, and a portion adapted to be engaged by said actuating pawl and the member depressed therethrough.

45 55. 42. In a time recorder, in combination, printing mechanism, an abutment adapted to limit the movement in one direction of a co-acting record card, a toothed member operatively connected with said abutment, actuating and holding pawls co-acting with 60 said toothed member, a supporting member, a spring-pressed member having a slotted connection with said supporting member at two points, portions of one of the slots being 65 inclined at right angles one with another,

means controlled in accordance with the position of said toothed member adapted to engage said spring-pressed member and throw a projecting portion thereof within the path of travel of said actuating pawl, said 70 projecting portion being adapted to be engaged by said actuating pawl and said spring-pressed member raised therethrough, said spring-pressed member adapted upon the same being raised to engage and render inoperative said holding pawl, and a projection upon said spring-pressed member adapted to be engaged by said actuating pawl and the member depressed therethrough.

75 43. In a time recorder, in combination, printing mechanism, an abutment adapted to limit the movement in one direction of a co-acting record card, a movable member operatively connected with said abutment, an actuating member and a holding member 80 co-acting with said movable member, means controlled by said movable member and operated by said actuating member adapted to throw said holding member into operative position, a clock-actuated member, a cam 85 pivoted upon said clock-actuated member eccentric to the axis thereof and adapted upon rotation to cause the operation of said actuating member, and a stop adapted to limit the movement of said cam away from 90 said axis.

95 44. In a time recorder, in combination, printing mechanism, an abutment adapted to limit the relative movement in one direction of a co-acting record card, a rod, a sleeve 100 mounted upon said rod and operatively connected with said abutment, a rack connected with said sleeve, a casing inclosing said printing mechanism and having an opening therein, a rotatably mounted indicator adjacent said opening and having characters thereon, and a pinion upon said indicator intermeshing with said rack, said several parts being 105 adapted visually to indicate the position of said abutment by the characters brought 110 opposite said opening.

45. In a time recorder, in combination, a casing having an opening therein, a member passing through said opening and adapted to move therein, and means controlled by said member and movable relatively thereto adapted to close said opening about the same.

115 46. In a time recorder, in combination, a casing having an opening therein, a member passing through said opening and adapted to 120 move therein, means adapted to close said opening about said member, and means controlling said last-mentioned means in accordance with the position of said member.

125 47. In a time recorder, in combination, a casing having an elongated opening therein, a lever projecting through said opening and adapted to travel from one end thereof to the other, a shutter adapted to close said opening about said lever, and an operative connection 130

between said shutter and said lever through which said lever is adapted in normal position to hold said shutter in closed condition.

48. In a time recorder, in combination, a casing having an elongated opening therein, a lever projecting through said opening and adapted to travel from one end to the other thereof, and a shutter adapted to close said opening about said lever, said lever being adapted to engage inclined surfaces upon said shutter and throw the same into and out of closed condition.

49. In a time recorder, in combination, a casing having an opening therein, a lever projecting through said opening and adapted to travel from one portion to another thereof, a shutter having an inclined slot therein, and means passing through said slot and mounting said shutter upon said casing, said shutter being adapted upon being raised to close said opening about said lever and said lever being adapted to engage portions of said shutter and throw the same into and out of closed position.

50. In a time recorder, in combination, a casing, an elongated opening therein, a lever projecting through said opening and adapted to travel from one end to the other thereof, and a shutter mounted upon said casing adjacent said opening by means passing through slots therein, inclined with reference to said opening, said shutter being adapted upon being raised to close said opening about said lever and said lever being adapted to engage inclined portions upon said shutter and throw the same into and out of closed condition.

51. In a time recorder, in combination, printing mechanism, means adapted to bring a record surface into engagement therewith, a rock shaft operatively connected to said means, an arm fixed upon said rock shaft and a manually-actuated lever pivoted eccentric to the axis of said rock shaft and having a slotted connection with said arm.

52. In a time recorder, in combination, printing mechanism, means adapted to bring a record surface into engagement therewith, a rock shaft operatively connected with said means, an arm fixed upon said rock shaft and a manually-actuated bell-crank lever pivoted eccentric to the axis of said rock shaft and having a slotted connection with said arm.

53. In a time recorder, in combination, printing mechanism, means adapted to bring a record surface into engagement therewith, a rock shaft operatively connected with said means, a manually-actuated bell-crank lever pivoted eccentric to the axis of said rock shaft, and an arm fixed upon said rock shaft and embracing the end of said bell-crank lever and having a slotted connection therewith.

54. In a time recorder, in combination, printing mechanism, means adapted to bring

a record surface into engagement therewith, a rock shaft operatively connected with said means, a manually-actuated bell-crank lever pivoted eccentric to the axis of said rock shaft and having a slotted connection with an arm fixed thereon, a casing inclosing said printing mechanism and having an opening therein through which said bell-crank lever passes, and means controlled in accordance with the position of said bell-crank lever adapted to close said opening about the same.

55. In a time recorder, in combination, a time-driven member, means continuously driven thereby, means intermittently driven thereby, and means adapted to oppose the movement of said first member with said intermittently driven means stationary and adapted to act in conjunction with said first member to move said intermittently driven means.

56. In a time recorder, in combination, a time-driven member, a printing wheel intermittently driven thereby, and means adapted alternately to be driven by and to tend to drive said first member, said means being adapted to tend to drive said first member during the actuation thereby of said intermittently driven printing wheel.

57. In a time recorder, in combination, a time-driven member, means intermittently driven thereby, and resilient means adapted to be compressed by said first member and adapted upon expanding to act in conjunction with said first member in driving said intermittently driven means.

58. In a time recorder, in combination, a time-driven member, a rotary member continuously driven thereby, means intermittently driven by said first member through said rotary member, and resilient means adapted to oppose the movement of said rotary member during a portion of each revolution and to aid the movement thereof during another portion of each revolution.

59. In a time recorder, in combination, a time-driven member, a minute wheel driven therefrom, an hour wheel intermittently driven by said minute wheel, and resilient means adapted to be tensioned by said minute wheel during a portion of each revolution thereof and adapted to contract and to tend to drive said minute wheel during another portion of each revolution thereof.

60. In a time recorder, in combination, a time-driven member, a minute wheel driven thereby, an hour wheel intermittently driven by said minute wheel, and a spring-pressed lever adapted to be moved by said minute wheel during a portion of each revolution thereof and adapted to tend to move said minute wheel during another portion of each revolution thereof.

61. In a time recorder, in combination, a time-driven member, a minute wheel driven thereby, an hour wheel intermittently driven

- by said minute wheel, means fixed upon said minute wheel, and a spring-pressed lever projecting within the path of travel of said last-mentioned means adapted to be engaged and moved by said means during a portion of each revolution of said minute wheel and adapted to engage and tend to move said means during another portion of each revolution of said minute wheel.
- 10 62. In a time recorder, in combination, a time-driven member, a minute wheel driven thereby, an hour wheel intermittently driven by said minute wheel, a member fixed upon said minute wheel, a spring-pressed lever projecting within the path of travel of said last-mentioned member adapted to be engaged and moved by said member during a portion of each revolution of said minute wheel and adapted to engage and tend to move said means during another portion of each revolution of said minute wheel, means upon said hour wheel adapted normally to prevent the movement thereof, and means adapted to release said last-mentioned means simultaneously with the driving of said hour wheel by said minute wheel.
- 15 63. In a time recorder, in combination, a time-driven member, a minute wheel driven thereby, an hour wheel intermittently driven by said minute wheel, a part mounted upon said minute wheel and adapted to be rotated therewith, and a spring-pressed lever mounted adjacent said minute wheel having a pair of inclined portions, one of which is adapted to be engaged by said part and said lever compressed during a portion of the revolution of said minute wheel, and the other of which is adapted to engage said part and tend to drive said minute wheel during another portion of the revolution thereof, said last-mentioned action taking place in conjunction with the driving of said hour wheel by said minute wheel.
- 20 64. In a time recorder, in combination, an hour printing wheel, means adapted intermittently to drive the same, and means adapted to prevent the retraction of said driving means during the actuation of said hour wheel.
- 25 65. In a time recorder, in combination, a time-driven member, a minute printing wheel driven therefrom, an hour printing wheel intermittently driven from said minute printing wheel, and means adapted to prevent the retraction of said minute printing wheel during the driving of said hour wheel.
- 30 66. In a time recorder, in combination, a time-driven member, a minute printing wheel driven therefrom, an hour printing wheel, means connecting with said hour wheel adapted to be engaged by parts connected with said minute wheel and said hour
- wheel driven throughout a predetermined distance, and means adapted to prevent the retraction of said minute wheel during the actuation of said hour wheel.
- 35 67. In a time recorder, in combination, a time-driven member, a minute printing wheel driven therefrom, an hour printing wheel intermittently driven from said minute wheel, and intermittently operative ratchet mechanism adapted to engage parts connected with said minute wheel and prevent the retraction thereof during the driving of said hour wheel.
- 40 68. In a time recorder, in combination, a time-driven member, an hour wheel intermittently driven therefrom, means adapted alternately to be driven by and to tend to drive said first member, and means adapted to prevent the retraction of said hour wheel driving means during the actuation of said hour wheel.
- 45 69. In a time recorder, in combination, a time-driven member, an hour wheel intermittently driven therefrom, and means adapted alternately to be driven by and to tend to drive said first member, said means being adapted to tend to drive said first member during the actuation of said hour wheel and said means being adapted to prevent the retraction of the driving parts during the driving of said hour wheel.
- 50 70. In a time recorder, in combination, a time-driven member, a minute wheel driven therefrom, an hour wheel intermittently driven from said minute wheel, and a spring-pressed member adapted to be engaged by parts upon said minute wheel and alternately to be driven by and to tend to drive said minute wheel, said means being adapted to prevent the retraction of said minute wheel during the driving of said hour wheel.
- 55 71. In a time recorder, in combination, a pair of rotatable and substantially co-axial members, said members being separable one from another, a projecting part upon one of the same engaging the other and adapted to transmit motion to or from the same, one of said rotatable members having irregularities in the surface thereof, and a movable member adapted to be thrown into engagement with said irregularities and positively lock said rotatable member in a predetermined position against movement in either direction.
- 60 72. In a time recorder, in combination, a casing, a pair of rotatable and substantially co-axial members positioned within said casing, said members being separable one from another, a projecting part upon one of said members adapted to engage the other and transmit rotary motion to or from the same, manually controlled means without said casing adapted to actuate one of said rotatable

members, and locking means within said casing adapted positively to lock said members against movement in either direction.

73. In a time recorder, in combination, 5 a casing, a rotatable member extending through said casing, a rotatable member adapted to co-act with said first-mentioned rotatable member and normally positioned coaxial with respect thereto, a projecting part 10 upon one of said rotatable members adapted to engage the other thereof and transmit motion to or from the same, said members being separable one from another, manually controlled means without said casing adapted to 15 impart a rotary movement to one of said rotary members, manually controlled locking means without said casing and independent manually-controlled locking means within 20 said casing each adapted to lock said rotatable members against movement in either direction.

74. In a time recorder, in combination, printing mechanism, means adapted to receive a co-acting record card and position the 25 same operatively with respect to said printing mechanism, a casing inclosing the said printing mechanism, means adapted to shift laterally said card receiving means, a rotatable member connected with said shifting 30 means, a door upon said casing, a rotatable member journaled within said door, one of said rotatable members being provided with a projecting portion eccentric to its axis adapted to engage the other of said rotatable 35 members and transmit motion to or from the same, manually controlled means positioned upon said door adapted to actuate said rotatable members, locking means without said casing, and independent locking means with- 40 in said casing, each of which is adapted to lock said rotatable members against movement in either direction.

75. In a time recorder, in combination, a casing having an opening therein, printing 45 mechanism within said casing, means adapted to throw a record receiving member into engagement with said printing mechanism, a rock shaft connected thereto, a manually-actuated lever pivoted eccentric to the axis 50 of said rock shaft, an arm fixed upon said rock shaft having a slotted connection with said lever, the free end of said lever passing through said opening in said casing, and means controlled by said lever adapted to 55 close said opening about the same.

76. In a time recorder, in combination, a casing having an opening therein, printing mechanism inclosed within said casing, means adapted to throw a record receiving member 60 into engagement with said printing mechanism, a rock shaft connected thereto, a manually-actuated lever passing through said opening and pivoted eccentric to the axis of

said shaft, an arm fixed upon said rock shaft having a slotted connection with said lever, a 65 shutter adapted to close said opening about said lever and an operative connection between said shutter and said lever through which said lever is adapted in normal position to hold said shutter in closed position. 70

77. In a time recorder, in combination, printing mechanism, means adapted to limit the relative movement in one direction of a co-acting record card, an actuating member adapted to move said limiting means, a holding member adapted to retain said movable means in the position into which it is moved, means controlled by said limiting means and operated by said actuating means adapted to throw said holding member into inoperative 80 position, means adapted to move a record receiving member laterally with respect to said printing mechanism, and means positioned within said casing adapted to lock said last-mentioned means positively against 85 movement in either direction.

78. In a time recorder, in combination, printing mechanism, means adapted to limit the relative movement in one direction of a co-acting record card, an actuating member 90 adapted to move said limiting means, a holding member adapted to retain said movable means in the position into which it is moved, means controlled by said limiting means and operated by said actuating means adapted to 95 throw said holding member into inoperative position, means adapted to move a record receiving member laterally with respect to said printing mechanism, means positioned within said casing adapted to lock said last-mentioned means positively against movement in either direction, and means adapted visually to indicate the position of said limiting means and of said lateral shifting means. 100

79. In a time recorder, in combination, a 105 casing, an element mounted thereon to swing relative thereto, a rotatable member journaled on the casing, a second rotatable member journaled on the swinging element, means associated with said members to 110 transmit rotary movement from one to the other, and manually operable means on said swinging element to rotate said members.

80. In a time recorder, in combination, a 115 casing, an element mounted thereon movable relative thereto, a rotatable member journaled on the casing, a second rotatable member journaled on said movable element, means associated with said members to transmit rotary movement from one to the other when the movable element is in one 120 position relative to the casing and which operatively disconnects said members when said element is in another position, and manually controlled means on said element 125 to rotate said second rotatable member.

81. In a time recorder, a rotating member, a second rotating member, means to intermittently drive the second member from the first member, means to rotate said first member, and means to give said first member an additional driving impulse at each actuation of said second member.

82. In a time recorder, in combination, a printing mechanism, and a card receiver comprising opposed members between which the card is received, means for moving said members simultaneously to have one of them take a determined position relative to the printing mechanism, and means to move the other member toward the first-named member subsequent to its positioning movement.

83. In a time recorder, in combination, a printing mechanism, a card receiver comprising opposed members between which a card is received, means to lock said members in a determined position relative to the printing mechanism, and means to move one of said members toward the other while in such position.

84. In a time recorder, in combination,

printing mechanism, a card receiver comprising opposed members between which a card is received, means to move said members simultaneously to take a determined position relative to the printing mechanism, manually controlled means to hold one of said members in such position, and means to move the other member toward the member so held.

85. In a time recorder, in combination, a printing mechanism, a card receiver comprising opposed members between which a card is received, means to move said members simultaneously to take a determined position relative to the printing mechanism, manually controlled means to hold one of said members in such position, and manually controlled means to move the other member toward the member so held.

In testimony whereof we affix our signatures, in the presence of two witnesses.

JOHN DEY.
ALEXANDER DEY.
